CLAIM

The ornamental design for a cleaner for a golf club head, as shown and described.

DESCRIPTION

FIG. 1 is a front elevation of a cleaner for a golf club head showing my new design;

FIG. 2 is a side elevation taken from the right of FIG.

1, the left side view being a mirror image thereof;

FIG. 3 is a top plan view thereof;

FIG. 4 is a bottom plan view thereof; and

FIG. 5 is a rear elevation thereof.

FIG. 1

FIG. 4
